UNITED STATES PATENT OFFICE.

JAMES P. BRACE, OF DRUMRIGHT, OKLAHOMA, ASSIGNOR, BY DIRECT AND MESNE ASSIGNMENTS, OF ONE-FOURTH TO OLIVER C. SHORT, OF DRUMRIGHT, OKLAHOMA, AND ONE-FOURTH TO ANDREW N. BOATMAN, OF OKMULGEE, OKLAHOMA.

FIGURE TOY.

1,413,958.

Specification of Letters Patent. Patented Apr. 25, 1922.

Application filed January 10, 1921. Serial No. 436,213.

To all whom it may concern:

Be it known that I, JAMES P. BRACE, a citizen of the United States, residing at Drumright, in the county of Creek and State 5 of Oklahoma, have invented certain new and useful Improvements in Figure Toys, of which the following is a specification, reference being had to the accompanying drawings.

10 This invention relates to toys and particularly to a figure toy capable of simulating movements of both man and beast.

Another object is to provide a toy of this character wherein movement of one body 15 member causes simultaneous movement of another body member supported by the first mentioned body member and wherein the second body member is movable independently of the first body member when the 20 first body member reaches the limit of its movement in one direction.

Another object of the invention is to provide a toy of this character including a wheel supported platform having a body 25 simulating an animal mounted on the platform, for movement relative to the platform, and a body or rider pivoted to the head of the animal and supported upon the back of the animal, the body of the rider 30 being arranged to move independently of the body of the animal when the rider is moved beyond the center of gravity by movement of the body of the animal.

A still further object of the invention is to 35 provide a toy of this character including a body member arranged for swinging movement, and a properly balanced body member arranged for swinging movement on and movement in unison with the first mentioned 40 body member.

With the above and other objects in view, the invention consists in the improved construction and arrangement of parts to be hereinafter more particularly described, 45 fully claimed and illustrated in the accompanying drawings, in which:—

Figure 1 is a side elevation of a toy constructed in accordance with an embodiment of the invention and showing the toy in one 50 position,

Figure 2 is a side elevation showing the toy in another position, and

Figure 3 is a detail view of the combined arm and rein.

Referring to the drawings, 5 designates a 55 platform having a front axle 6 and a rear axle 7, the rear axle being provided with a crank 8, the purpose of which will be hereinafter described. Carried by each axle is a pair of wheels 9, the wheels connected to the 60 axle 7 forming a part of the operating mechanism when the base is in motion. A slot 10 is provided in the base, and extends longitudinally and centrally of the platform, while carried by the rear portion 11 of the base is 65 a weight 12. If desired, the rear portion 11 may be made relatively thick so as to take the place of the weight. The purpose of the weight is to prevent the platform from tilting when the figures are in operation. 70

A body member 13 is provided, said body member may be constructed to simulate any type of animal such as a horse, mule, etc. The fore legs 14 of the animal or body member are pivoted as at 15 to the body 75 member 13. The hoofs or lower portions of the fore legs are embedded in the forward portion of the base 5, so as to maintain the fore legs stationary and provide a support for the body member 13. By this means, the 80 body member including the hind legs is adapted to oscillate with respect to the fore legs in the operation of the toy. An operating rod 16 is connected at its end 17 to the crank 8 of the shaft 7, the rod 16 extending 85 through the slot 10 and between the fore legs 14 so that movement of the crank shaft will impart movement to the rod 16. The end 18 of the rod is extended substantially at right angles to the rod and passed through 90 an opening 19 provided in the head of the animal or body member 13 in spaced relation to the pivotal connection 15. By this means movement of the rod 16 will cause movement of the body member 13. 95

A body 20 is provided, said body may be constructed to simulate a rider of any desired character, for instance, an Indian. The legs 21 of the rider are adapted to straddle the body member 13, while the trunk of 100 the rider is adapted to rest on the back of the body member 13, to limit movement of the rider in one direction. Secured to the upper portion of the trunk of the rider is a pair of arms 22, said arms being adapted to 105 move with the body of the rider. Projecting from the end portion of each arm or hand of the rider is an extension 23 which is

formed integral with the hand and is constructed to simulate a rein, the end 24 of the extension being mounted on the end 18 of the rod 16. By this novel construction 5 each arm and rein serves as a lever by means of which the body of the rider is permitted to move independently of the body of the animal at certain times, one of the extensions 23 being disposed on each side of the 10 head of the body 13. Carried by the head, in spaced relation to the end 18 of the rod is a pair of oppositely extending stops 25 adapted at certain times to limit movement 15 of the body 20 by contact with the extensions or reins 23.

In the operation of the device, the base 5 is drawn along the floor or ground and thereby causes rotation of the shaft 7, the crank of the shaft imparts rotary movement to the rod 20 16 which in turn raises the rear portion of the body member, and at the same time causes movement of the rider with the body member until the reins and arms of the rider pass the center of gravity. At this point the body 25 member 13 reaches the limit of its movement, but the rider is permitted to move independently of the body member towards and beyond the head of the body member through the medium of gravity. By this novel arrangement 30 the body of the animal simulates the movement of a balking or kicking animal, while the rider is permitted to move independently of the body member to give the appearance of the animal throwing the 35 rider. After the body member reaches the limit of its movement in one direction, as above stated, the body 20 is swung from the back of the body member 13, and supported by the arms 22 and reins 23 in a position 40 above and beyond the head of the body member. Continued rotation of the shaft 7 will cause the rear portion of the body member 13 to swing towards the platform 5, thereby causing the reins 23 and arms 22 to swing the rider 45 upwardly. Continued movement of the body member towards the base will again shift

the body of the rider beyond the center of gravity and cause the same to descend into engagement with the back of the body member 13. The rider and animal are thereby 50 caused to assume an inactive position.

An important feature of this invention is that the only operating mechanism necessary is the crank shaft 7 and the rod 16, the force of gravity accomplishes the rest of the operation. Another important feature is that the body of the animal is not only movable with respect to the base, but the body of the rider is also movable with respect to the animal and the base so that a variety of 60 movements is possible from which an unlimited amount of amusement may be derived and all of these features are possessed by a toy that is simple in construction.

What is claimed is:—

A figure toy comprising a wheel supported base, one pair of said wheels being mounted on a crank, a body member having one portion thereof secured to the base, the remaining portion of said body member being pivoted to the stationary portion of said body member, a rod connected at one end to the crank of the axle, the opposite end of said rod being extended at right angles and through the forward end of the movable portion of the body member, a second body member movably mounted on the first mentioned body member, said second mentioned body member having arms projecting therefrom, the ends of said arms being mounted on the last mentioned end portion of the rod, stops carried by the forward end of the first mentioned body member, said stops being adapted to engage the arms of the second mentioned body member to hold the second mentioned body member in spaced relation to the first mentioned body member and beyond one end of the base.

In testimony whereof I hereunto affix my signature.

JAMES P. BRACE.
